UNITED STATES PATENT OFFICE.

ABRAHAM LAPATIN, OF NEW YORK, N. Y., ASSIGNOR TO STAR PLEATING CO., OF NEW YORK, N. Y., A CORPORATION OF NEW YORK.

DESIGN FOR AN EMBROIDERED TEXTILE FABRIC.

Application filed October 31, 1923. Serial No. 7,637. Term of patent 3½ years.

To all whom it may concern:

Be it known that I, ABRAHAM LAPATIN, a citizen of the United States of America, and a resident of the borough of Manhattan, city, county, and State of New York, have invented a new, original, and ornamental Design for an Embroidered Textile Fabric, of which the following description, in connection with the accompanying drawing, is a specification.

The single figure of the drawing is a plan view of the embroidered textile fabric showing my new design.

I claim as my invention:

The ornamental design for an embroidered textile fabric as shown.

ABRAHAM LAPATIN.
